(57) **CLAIM**

I claim the ornamental design for a chair, as shown and described.

DESCRIPTION

FIG. 1 is a front perspective view of a chair;
FIG. 2 is a front view of the chair of FIG. 1;
FIG. 3 is a rear view of the chair of FIG. 1;
FIG. 4 is a right side view of the chair of FIG. 1;
FIG. 5 is a left side view of the chair of FIG. 1;
FIG. 6 is a top plan view of the chair of FIG. 1; and,
FIG. 7 is a bottom plan view of the chair of FIG. 1.
The dash-dash broken lines shown in the drawings are for
the purpose of illustrating portions of the article that form no
part of the claimed design.

1 Claim, 7 Drawing Sheets
